UNITED STATES PATENT OFFICE.

LOUIS HOFFMAN, OF DULUTH, MINNESOTA.

SAD-IRON.

1,241,216.

Specification of Letters Patent. Patented Sept. 25, 1917.

Application filed February 3, 1917. Serial No. 148,507.

To all whom it may concern:

Be it known that I, LOUIS HOFFMAN, a citizen of the United States, residing at Duluth, in the county of St. Louis and State 5 of Minnesota, have invented certain new and useful Improvements in Sad-Irons, of which the following is a specification, reference being had therein to the accompanying drawing.

10 This invention resides in certain improvements in sad irons and relates particularly to electrically heated sadirons.

The principal object of the invention is to produce a simple and practical iron of 15 this character having means therein whereby either steam or water, or any desired mixture thereof may be applied to the goods being ironed through the face of the iron.

Other objects and advantages of my novel 20 combination will appear in the further description of the device.

In the accompanying drawings forming part of this application:

Figure 1 is a vertical longitudinal central 25 sectional view of my improved sad iron, illustrating a portion thereof in elevation.

Fig. 2 is a top plan view of the base of 30 the iron illustrating the arrangement of perforations therethrough and partition walls, and

Fig. 3 is a top plan view of the iron with a portion of the handle attachment removed.

1 represents the base which compared with other parts of the iron is comparatively 35 thick and heavy, it being formed preferably of cast metal, and having in the upper face thereof, a series of inter-communicating open transverse channels or conduits 2. The conduits 2 are preferably of rectangular 40 form in cross section, are parallel with each other and extend from one side of the base to the other with the exception of a small marginal portion 3 extending wholly around the base. The cross conduits 2 communicate 45 with a central longitudinal similar conduit 4 in which is supported a steam and water distributing pipe 5 and which pipe is provided with opposed perforations 6 opposite each transverse conduit 2, whereby the contents of the pipe may be forced directly and simultaneously into both sections of each transverse conduit. I have shown the conduit 4 as being irregular in longitudinal extent, it having a reverse curve therein to 50 avoid other supporting means in the iron

construction, but this is simply for convenient adaptation of my improvement to a form of iron already in use. Numerous nozzle holes 7 are spaced an equal distance apart and formed in the bottom of each 60 conduit 2, each hole 7 terminating in a reduced nozzle perforation 8 through the face 9 of the iron. The object of the discharge holes being formed in this way, aside from convenience in manufacture, is to provide 65 means whereby the steam generated in the iron may be maintained as hot and as active as possible within close proximity to its point of discharge.

The division walls 10 separating the conduits 2 are preferably of substantially the same width of the conduits to accomplish as nearly as possible, even distribution of heat throughout the base of the iron.

A metal covering plate 11, preferably of 70 copper, rests upon the upper face of the base 1, and is held tightly thereupon by the screw threaded through bolts 12 and 13, which are also screw threadedly attached to the base in suitable blank places 14 and 15, 75 left therefor in the base.

The electric heating element rests upon the cover plate 11 and is composed of any suitable electric resisting material 16 connected with the electric circuit, as indicated 80 at 17 and 18 and surrounded by suitable insulation indicated at 19, this arrangement of heating device being common in the art. On top of the heating element rests directly the steam generating receptacle 20, it covering 90 practically the entire surface of said element whereby an amount of heat substantially equal to that distributed to the base of the iron is applied to the receptacle.

The receptacle 20 has formed therein a 95 longitudinally inclined chamber 21, the forward end thereof being somewhat higher than the rear end, said chamber occurring intermediate the through bolts 12 and 13 which loosely pass vertically through the 100 solid ends of the receptacle. Nuts 22 and 23 surround the bolts 12 and 13 above the receptacle and are designed to hold the latter in position upon the heating element by being screwed tightly thereupon.

The distributing pipe 5 has formed preferably integral therewith an upwardly extending branch 24 which is screw threaded through the covering plate 11 and the under wall of the receptacle 20 into the chamber 110

21 and adjacent the forward end thereof. Directly above the branch pipe 24 and screw threadedly attached through the wall of the receptacle above the chamber 21, is a small 5 cylinder 25, the lower end of which is solid, as at 26 and the upper end open for application of the operative mechanism therein. The lower end of the water supply cylinder 25 is made in the form of a discharger nozzle 27 10 pointing directly downward into the open end of the branch pipe 24, though but partly fills the open end of said branch. This nozzle has a small aperture 28 therethrough, the upper end of which terminates in a valve 15 seat for the conical shaped valve 29 on the end of the stem 30 and which valve is held normally seated by a suitable expansive spiral spring 31 surrounding the stem 30 and thrusting against the upper face of the 20 valve at one end and the lower face of the screw plug 32 at the other end. A screw threaded stuffing gland 33 is mounted within the plug 32 to form a tight joint about the stem which protrudes therefrom. A nut 34 is fixed upon the extreme upper end of the stem and spaced a distance above the gland 33, the object of which will be described later.

Adjacent the lower rear end of the chamber 21 and near one corner thereof, is the water supply pipe 35, it being screw threaded through the upper wall of the chamber. This pipe extends upwardly through the upper wall of the iron housing 36 and just 35 above same is connected to a horizontal cylinder 37 which carries a reciprocal valve 38 and stem 39 which control the flow of water therethrough into the chamber 21. This valve and operation thereof is similar 40 to that within the cylinder 25, except that an inward motion of the valve stem 39 opens the valve, whereas in the former, an outward motion of the stem opens the valve. It is not considered necessary to further describe the details and operation of this 45 valve, as they are well known in the art.

The mechanism for operating the stem 39 will be described later. A suitable water supply pipe 40 is connected at 41 to the cylinder 37 and at its opposite end to the cylinder 25 at 42. A branch 43 is connected with the pipe 40 and is provided with any suitable form of valve connection 44 to which the water hose may be attached and 55 by which a constant supply of water under pressure is had. The housing 36 rests about its entire lower edge upon the cover plate 11 and is held tightly there against by suitable nuts 45 and 46 upon the upper screw threaded 60 ends of the bolts 12 and 13. An upwardly extending boss 47 is formed upon the upper wall of the housing about each bolt 12 and 13 and upon which rests the handle supporting member 48, the nuts 45 and 46 securely holding said member in place.

The upwardly inclined portions 49 and 50 of the handle member 48 support intermediate their free ends the handle 51.

A narrow slot 52 is cut in the under forward half of the handle 51 and in which slot 70 the valve manipulating finger levers 53 and 54 extend, their extreme free ends only projecting normally beyond the borders of the slot and whereby the levers are made conveniently accessible to the fingers of the operator's hand while grasping the handle. The lever 53 is pivotally mounted at 55 upon the arm 56 of the double armed bracket 57 secured to the inclined portion 50 of the handle supporting member by suitable 80 screws 58-58. A relatively short portion 59 of the lever 53 extends beyond the pivotal point 55 and is pivotally connected at 60 to a rod 61, the opposite end of which is pivotally connected at 62 to one end of the valve 85 operating rod 63, which is pivotally mounted at 64 within the arm 65 of the bracket 57, the opposite end 66 of the lever being forked or surrounding the valve stem 30 beneath the nut 34, and by which, lever the 90 valve stem is raised when the free end of the lever 53 is raised. The lever 54 is gracefully arched to form as little obstruction as possible, a portion of which extends parallel with the inclined portion 50 of the handle 95 supporting member and is pivotally mounted as at 67 upon a suitable bracket 68 fixed to the member 50 by the screw bolt 69. The end 70 of the lever 54 is arched transversely so as to engage the outer end 71 of the valve 100 stem 39 and by which said stem is operated inwardly by an upward motion of the handle end of the lever 54, such operation tending to open the valve in the cylinder 37, as before described. Upon the portion 49 of 105 the handle supporting member 48 is rigidly fixed a rectangular shaped open guard 72 for the protection of the electric plug 73, as is commonly used upon such devices.

From the foregoing it is evident that I 110 have produced a simple and compact electric heated sad iron having means whereby steam or water or any desired combination of both may be quickly and conveniently applied to the goods being pressed.

Having thus described my invention what I claim as new and desire to secure by Letters Patent, is:

1. A sadiron of the character described, comprising in combination a base having a 115 plurality of transverse conduits therein with perforations in the conduits through the face of the iron and a longitudinal conduit communicating with the transverse conduits, a perforated distributing pipe extending the 120 full length of the longitudinal conduit, a covering plate on top of the base, a heating element resting upon the covering plate, a chambered steam generator resting upon the heating element, a pipe connection between 125 130

the perforated distributing pipe and the steam generating chamber, a water supply for the steam chamber, a water supply for the pipe connection with the perforated pipe and means for controlling the water supplies 5 independently or simultaneously, substantially as and for the purpose described.

2. A sadiron of the character described, comprising in combination a base having a plurality of transverse conduits therein with 10 perforations in the conduits through the face of the iron and a longitudinal conduit communicating with the transverse conduits, a distributing pipe extending the full length 15 of the longitudinal conduit and having perforations therein communicating with each transverse conduit, a covering plate on top of the base, a heating element on top of the covering plate, a chambered steam generating 20 receptacle on top of the heating element, a pipe connection between the perforated distributing pipe and the steam generating chamber, a water supply for the chamber, a water supply for the pipe connection passing 25 through the chamber and means for controlling the water supplies independently or simultaneously.

3. The combination with a sadiron of the character described, having a perforated cellular base and a perforated distributing pipe 30 within the cells in the base, and a heating

element resting upon the base, of a steam generating receptacle having an inclined chamber therein, a pipe connection between the chamber and the perforated distributing 35 pipe, a water supply pipe communicating with the lower end of the chamber, a water supply passing through the upper end of the chamber and discharging directly into the pipe connection though not attached 40 thereto, and means for controlling the water supplies independently or simultaneously, substantially as and for the purpose described. 45

4. The combination with a heated sadiron of the character described, having steam generating means therein, a perforated base communicating with the steam generator, a water supply connected with the iron of two independently controlled water circuits 50 within the iron, one of which discharges directly into the steam generator and the other discharging through the steam generator to the perforated base of the iron, substantially 55 as and for the purpose described.

In testimony whereof I hereunto affix my signature in the presence of two witnesses.

LOUIS HOFFMAN.
